[57] CLAIM

The ornamental design for a pet carrier bag, as shown and described.

DESCRIPTION

FIG. 1 is an environmental, perspective view of a pet carrier bag showing my new design;

FIG. 2 is a front elevational view thereof;

FIG. 3 is a left side elevational view with the right side being a mirror image thereof;

FIG. 4 is a top view thereof;

FIG. 5 is a bottom view thereof; and,

FIG. 6 is a rear elevational view thereof.

The broken line showing of a person wearing the pet carrier bag and a pet in the pet carrier bag is for illustrative purposes only and form no part of the claimed design.
